United States Patent Office

Des. 186,109

Patented Sept. 15, 1959

186,109

COMBINED SCABBARD AND LETTER HOLDER

Don Harley, St. Paul, and Cecil B. Woofter, Minneapolis, Minn., assignors to Arthur Salm Inc., Chicago, Ill., a corporation of Illinois

Application August 8, 1958, Serial No. 52,121

Claims priority, application Germany May 23, 1958

Term of patent 14 years

(Cl. D22—6)

Fig. 1 is a perspective view of a combined scabbard and letter holder showing our new design, the broken line illustration of a letter opener and scissors being for illustrative purposes only;

Fig. 2 is an end perspective view thereof as it appears with the letter opener and scissors removed therefrom;

Fig. 3 is a side elevational view with the letter opener and scissors removed;

Fig. 4 is a top plan view; and

Fig. 5 is an end elevational view thereof.

We claim:

The ornamental design for a combined scabbard and letter holder, substantially as shown and described.
